HINGE ROD PIVOT

Joseph L. Shaw, Dunlap, Ind., assignor to
Buescher Band Instrument Company, Elkhart,
Ind.

Application July 22, 1940, Serial No. 346,838

3 Claims. (Cl. 84—380)

This invention relates to musical instruments and more particularly to an improved key mounting means for a wind instrument such as in a saxophone, clarinet, oboe or the like.

5 An object of this invention is to provide an improved mounting means for mounting the key shafts on the saxophone, clarinet, oboe or other musical instrument, the mounting means being of such construction as to reduce the friction 10 between the key shaft and the supporting posts therefor.

15 At the present time, it is the practice in mounting key shafts to provide one of two types of mountings, one mounting includes a stationary hinge screw which is extended through one supporting post and threaded into a second supporting post. This stationary hinge screw, however, frictionally contacts throughout its 20 length with the inner surface of the tubular key shaft and thus forms a long frictional surface which retards the rocking of the tubular shaft after the instrument has been in use for a short time. The second type of mounting includes 25 pinions threaded through the supporting posts and provided with tapered ends engaging the ends of the shaft. It is, therefore, another object of this invention to eliminate the stationary shaft for the tubular key shafts and the tapered pinions by providing a pair of shortened 30 stub shafts which are rockable relative to the supporting posts but are fixed relative to the key shaft.

35 A further object of this invention is to provide a key shaft mounting means for a wind instrument whereby end play between the bearing posts and the shaft may be readily taken up.

40 Embodying the objects aforesaid and others which may hereinafter appear, the invention consists of the novel construction, combination and arrangement of parts as will be more specifically described and illustrated in the accompanying drawing, wherein is shown an embodiment of the invention, but it is to be understood that changes, variations and modifications 45 may be resorted to which fall within the scope of the invention as claimed.

In the drawing:

50 Figure 1 is a fragmentary detail side elevation of a second instrument having a key shaft mounting means constructed according to an embodiment of this invention,

Figure 2 is a sectional view partly broken away taken on the line 2—2 of Figure 1, and

55 Figure 3 is a fragmentary sectional view of a modified form of pivot screw.

Referring to the drawing, the numeral 10 designates a branch or body for a musical instrument such as a saxophone, clarinet, oboe or the like. The branch or body 10 is provided with a socket or tone hole 11 and a pad 13 is adapted to engage the socket 11. The pad 13 is carried by a pad supporting arm 12 which is fixed to an elongated key shaft 14. The key shaft 14 at the end thereof opposite from the supporting arm 12 is provided with a key 15 which is connected to the shaft 14 by means of a substantially L-shaped connecting member 16.

The shaft 14 is disposed between a pair of outstanding supporting posts 17 and 18 which are fixed to the exterior of the branch or body 10.

In order to provide a means whereby the shaft 14 may be rockably supported from the posts 17 and 18, I have provided a pair of stub shafts generally designated as 19 and 20. The stub 20 shaft 19 is formed with a cylindrical part 21 having a head 22 on its outer end which is formed with a kerf 23. A threaded reduced part 24 is carried by the inner end of the cylindrical part 21 and is adapted to threadably engage in 25 a threaded bore 25 formed in the adjacent end of the shaft 14.

The shaft 19 is also formed with a reduced diameter cylindrical stud 26 extending inwardly from the threaded part 25 and the stud 26 engages in a reduced counterbore 27 of the shaft 14. The outer part 21 of the shaft 19 is rotatable in an opening or bearing 28 formed in the post 18 and when the shaft 19 is threaded into the adjacent end of the shaft 14, the shaft 19 35 may be locked against rotation relative to the shaft 14 by means of a set screw 29 which extends through the shaft 14 and engages the reduced stud 26.

The stub shaft 20 comprises a cylindrical body 40 39 formed with a head 31 having a kerf 32 therein and the body 39 is rotatable in an opening or bearing 33 formed in the post 17. The shaft 20 inwardly from the body 39 is formed with a threaded part 34 which threadably engages a 45 threaded bore 35 formed in the adjacent end of the shaft 14. A reduced stub shaft 36 extends axially inwardly from the threaded part 34 and engages loosely in the counterbore 27 of the shaft 14. A set screw 37 is threaded through 50 the shaft 14 and engages the stub shaft 36 so as to lock the shaft 20 relative to the shaft 14.

With a key mounting means as herein disclosed, the key shaft is provided with relatively short bearing surfaces which in the present in- 55

stance are formed in the supporting posts so that the key shaft will have relatively short frictional bearings adjacent each end thereof and at a point outwardly of each end. In addition if there should be any end play between the heads 22 and 31 with respect to the posts 13 and 17, respectively, the stub shafts 19 and 20 may be threaded inwardly of the shaft 14 by loosening the set screws 29 and 37.

10 While I have shown only one key shaft and key on the branch or body 10, it will, of course, be understood that the branch or body 10 will be provided with the usual number of keys, the structure herein disclosed being merely illustrative of the manner of mounting the key shafts on the branch or body. The key shaft 14 at a point inwardly from one end thereof is provided with a right angularly disposed arm 38 which is fixed to the shaft 14 and which is adapted 15 to contact with the tone pipe 10 so as to limit the opening of the valve 13.

In order to reduce any wear which should occur in the posts 17 and 18, the openings 33 and 28, respectively, may be provided with replaceable bushings or bearing sleeves 33^a and 28^a, respectively. The bushings 33^a and 28^a may be formed of material different from the posts 17 and 18 so as to resist wear.

In Figure 3 there is shown a modified form of 20 pivot screw wherein a pivot screw designated generally as 20^a is secured to a shaft 14^a and is rotatable in a supporting post 17^a. The pivot screw 20^a is formed with a threaded part 24^a, which threadably engages in a threaded bore 25^a formed 25 in the shaft 14^a. A reduced stud 26^a is carried axially by the screw 20^a at its inner end and engages in a reduced counter bore 27^a formed in the shaft 14^a. The bores 25^a and 27^a are substantially longer than the threaded part 24^a and the stud 26^a respectively, so that the screw 20^a may be adjusted endwise of the shaft 14^a to take up wear.

The outer portion of the screw 20^a is formed with a frusto-conical bearing shaft or head 21^a having a kerf 23^a in its outer end. The bearing shaft or head 21^a is rotatable in a frusto-conical bearing bore 28^b formed in a supporting post 18^a. The screw 20^a is adapted to be held in fixed adjusted position with respect to the shaft 14^a by means of a set screw 29^a which is threaded through the shaft 14^a and which engages the stud 26^a.

By the use of the tapered bearing part 21^a any wear between the post 18^a and the bearing part 21^a may be readily taken up by releasing the set

55 screw 29^a and threading the screw part 24^a inwardly of the shaft 14^a.

What I claim is:

1. A means for rockably mounting a musical instrument key shaft between a pair of supporting posts, comprising a pair of stub shafts having a smooth bearing surface for engagement with a smooth opening formed in a post, a threaded part extending axially from said smooth bearing surface and having a diameter less than the diameter of said bearing surface, a reduced diameter cylindrical stud extending axially from said threaded part, said shaft having a threaded bore extending inwardly from an end thereof and a reduced diameter counterbore extending inwardly from said threaded bore, and a set screw threadably engaging through said key shaft and contacting with said stud to hold said stub shaft against rotation relative to said key shaft.

2. A means for rockably mounting a musical instrument key shaft between a pair of supporting posts, comprising a pair of stub shafts having a smooth cylindrical bearing surface for engagement with a smooth cylindrical opening formed in a post, a threaded part extending axially from said smooth bearing surface and having a diameter less than the diameter of said bearing surface, a reduced diameter cylindrical stud extending axially from said threaded part, said shaft having a threaded bore extending inwardly from an end thereof and a reduced diameter counterbore extending inwardly from said threaded bore, and a set screw threadably engaging through said key shaft and contacting with said stud to hold said stub shaft against rotation relative to said key shaft.

3. A means for rockably mounting a musical instrument key shaft between a pair of supporting posts, comprising a pair of stub shafts having a smooth tapered bearing surface for engagement with a smooth tapered opening formed in a post, a threaded part extending axially from said smooth bearing surface and having a diameter less than the diameter of said bearing surface, a reduced diameter cylindrical stud extending axially from said threaded part, said shaft having a threaded bore extending inwardly from an end thereof and a reduced diameter counterbore extending inwardly from said threaded bore, and a set screw threadably engaging through said key shaft and contacting with said stud to hold said stub shaft against rotation relative to said key shaft.

JOSEPH L. SHAW.
